[57] ABSTRACT

A system for controlling a solvent refining unit so as to operate the refining unit at the maximum limit of its operating parameters. Three such operating parameters are the refining temperature which is limited by the miscibility of charge oil and the solvent, the flow rates of extract oil and refined oil, which are limited by the mechanical design of the refining unit, obtained from the refining of the charge oil. A plurality of computers determine the values of constants from equations, hereinafter disclosed, so that the operating parameter that is limiting may be determined. A plurality of analog computers generate control signals for the different limiting operating parameters. Switching means apply the proper control signals to the refining unit in accordance with the determination of which operating parameter is limiting.

FIG. 6

MEANS AND METHOD FOR CONTROLLING A SOLVENT REFINING UNIT FOR MAXIMUM YIELD

BACKGROUND OF THE INVENTION

1. Field of the Invention

The present invention relates to control systems and, more particularly, to a control system for a solvent refining unit.

2. Description of the Invention

Heretofore, control systems for solvent refining units, such as disclosed in U.S. application Ser. No. 96,193, filed Dec. 8, 1970 by Robert A. Woodle, inventor of the present invention, and assigned to Texaco Inc., assignee of the present invention, provide optimum control of the refining unit. However, it may be profitable to operate a solvent refining unit at its maximum capability even though that operation is not an optimum operation. The control system of the present invention determines which operating parameter is limiting the yields of extract oil and refined oil from a solvent refining unit and provides control of the solvent refining unit accordingly to achieve a maximum operating capability while yielding refined oil of a desired quality.

SUMMARY OF THE INVENTION

A system controls a solvent refining unit which treats charge oil with a solvent in a refining tower to yield raffinate and extract mix. The solvent is separated from the raffinate and from the extract mix by strippers to provide refined waxy oil and extract oil, respectively. The solvent is then returned to the refining tower. This control system comprises control devices receiving control signals which cause the refining unit to operate for a predetermined time period at a predetermined solvent dosage-temperature combination for providing refined oil of a desired quality. At least one condition of the extract oil and the refined waxy oil is measured by a circuit which provides corresponding signals. Another circuit measures at least one property of the charge oil and provides a signal corresponding thereto. A signal source provides signals corresponding to the limitation of the refining unit and the refining operation. A network determines which operating parameter is limiting the refining of the charge oil from the measurement signals and the signals from the signal source and provides corresponding control signals to the control device. The operation of the refining unit is controlled after the predetermined time period by the last mentioned control signals.

One object of the present invention is to provide a system controlling a refining unit so that the refining unit operates at a maximum capability.

Another object of present invention is to operate a solvent refining unit at a refining temperature that is substantially lower than the temperature at which the solvent and charge oil becomes miscible.

Another object of the present invention is to operate a refining unit at a maximum refined oil flow rate to yield refined oil of a desired quality.

Another object of the present invention is to operate a refining unit at a maximum extract oil flow rate to yield refined oil of a desired quality.

Another object of the present invention is to provide a system which determines which operating parameter

of a refining unit is limiting and controls the refining unit accordingly.

The foregoing and other objects and advantages of the invention will appear more fully hereinafter from a consideration of the detailed description which follows, taken together with the accompanying drawings wherein one embodiment of the invention is illustrated by way of example. It is to be expressly understood, however, that the drawings are for illustration purposes only and are not to be construed as defining the limits of the invention.

DESCRIPTION OF THE DRAWINGS

FIG. 1 is a simplified block diagram of a system, constructed in accordance with the present invention, for controlling a solvent refining unit so that solvent refining unit operates at a maximum capability.

FIG. 2 is a graphic representation of a correlation of the viscosity of charge oil versus a mathematical constant n .

FIGS. 3, 4, 5, and 6 are detailed block diagrams of the b constant computer, the EO_{LIM} , RO_{LIM} , and CO_T computers.

DESCRIPTION OF THE INVENTION

The aforementioned U.S. application is for a system providing optimum control of a solvent refining unit. However, it may be desirable to operate the refining unit at its maximum capability even though the operation may not be optimum. There are at least three operating parameters that limit the capability of the refining unit and they are the refined oil flow rate, the extract oil flow rate and the miscible temperature. The miscible temperature is that temperature at which the charge oil dissolves completely in the solvent. The flow rates are limited by the physical design of the refining unit.

Referring to FIG. 1, there is shown a system for controlling a conventional type solvent refining unit to operate at its maximum capability where the solvent is N-methyl-2-pyrrolidinone. The rate of the flow of the charge oil is controlled so as to regulate the flow rates of refined waxy oil and the extract oil. The temperature, which is also controlled, at which the refining of the crude oil takes place affects the yield of the refined oil and the extract oil. The rate of the charge oil entering a refining tower 3 in a line 4 is sensed and controlled by conventional types sensing element 5, flow recorder controller 6 and valve 2. Sensing element 5 provides a signal to controller 6 corresponding to the flow rate of the charge oil. Controller 6 operates valve 2 to control the rate of flow of the charge oil to tower 3 in accordance with the signal from sensing element 5 and a signal E_1 . Signal E_1 controls the set point of controller 6.

Although not shown, for ease of explanation, the charge oil and refining solvent entering tower 3 through lines 4 and 7, respectively, have been heated to a predetermined temperature. Tower 3 contains packing 8 where the charge oil and solvent are contacted in counter current flow effecting the extraction of low viscosity index constituents of the crude oil. Raffinate including the refined waxy oil and a small amount of dissolved solvent is withdrawn through a line 10.

A temperature gradient is maintained in tower 3 by means of a cooling coil 11 having cooling water flowing through it. The temperature in tower 3 is sensed by conventional type sensing means 12 which provides a corresponding signal to a temperature recorder controller 14. Temperature recorder controller 14, which may be of a type well known in the art, operates a valve 15 in accordance with the signal from temperature sensing means 12 and a signal E_{19} . Signal E_{19} controls the set points of temperature recorder controller 14. Valve 15 controls the rate of flow of the cooling water to control the temperature in tower 3.

Raffinate in line 10 enters a stripper 15 which strips the solvent from the raffinate to yield the refined waxy oil. The solvent is returned to tower 3 by line 7 while the refined waxy oil is provided to dewaxing means 16 through a line 17. Dewaxing means 16 removes the wax and provides refined oil for storage and blending with product lubricating oil. Elements having a numerical designation with a suffix are identical in operation and connection as elements having the same numerical designation without a suffix.

Sensing means 5A and a conventional type flow transmitter 20 measures the rate of flow of the refined waxy oil from stripper 15 and provides a corresponding signal E_2 .

Extract-mix comprising solvent and dissolved low viscosity index constituents of the charge oil is withdrawn from tower 3 through a line 22 at a temperature controlled by cooling coil 11. The extract-mix in line 22 is passed to a stripper 23 where the solvent is stripped from the extract oil which is discharged through a line 25. The recovered solvent is withdrawn through line 7 for return to tower 3 and re-use. The flow rate of the solvent is maintained at a maximum and the solvent dosage is controlled by controlling the flow rate of the charge oil. Sensing means 5B and a flow transmitter 20A senses the rate of flow of extract oil in line 25 and provides a corresponding signal E_3 . Initially the refining of the charge oil is done at a solvent dosage and temperature selected from various combinations of solvent dosage and temperature that yield the desired quality of refined oil. A source 26 of direct current voltage provides variable amplitude voltages E_A , E_B corresponding to a selected flow rate CO_{SEL} for the charge oil and to the selected temperature T_{SEL} . A switch 27 which may be of the 'momentary on' double pole single throw type is activated to momentarily apply voltages E_A , E_B as signals E_1 and E_{19} , respectively, to flow recorder controller 6 and to temperature recorder controller 14, respectively, to adjust the set points so that the refining is initially performed at the selected solvent dosage-temperature combination. The selected dosage S_{SEL} is related to the selected flow rate by the following equation:

$$S_{SEL} = (SOL_{LIM} / CO_{SEL}) (100) \quad (1)$$

A sample of the charge oil in line 4 is continuously applied to a viscosity meter 28, which may be of the type described by J. M. Jones, Jr. in U.S. Pat. Nos. 2,791,902 and 3,025,232. The effluent from meter 28 may be returned to tower 3 or discarded as slop. Viscosity meter 28 provides an analog signal E_4 , corresponding to the viscosity of the charge oil at 210°F, to a conventional type analog-to-digital converter 29

which converts analog signal E_4 to a digital signal. The digital signal from the analog-to-digital converter 29 controls a memory 30, which may be of a diode type with logic gating that is well known to one skilled in the art, to provide a digital signal corresponding to a characteristic constant n . The values of n as related to the viscosity of charge oil, shown in the form of a graph in FIG. 2, are stored in memory 30 and the digital signal from converter 29 controls the logic gating in memory 30 to pass the signal corresponding to the proper value of n . The digital signal from memory 30 is converted to an analog signal E_5 by a digital-to-analog converter 31.

The n constant is used to calculate a constant a in accordance with the following equation:

$$a = RO_M / (EO_M)^n \quad (2)$$

where RO_M is the measured flow rate of the refined waxy oil and EO_M is the measured flow rate of the extract oil. Signals E_2 and E_3 , corresponding to the measured flow rates of RO_M , EO_M of the refined waxy oil and the extract oil, respectively, and signal E_5 are applied to an a constant computer 34, which provides a signal E_6 corresponding to the a constant. Computer 34 raises the measured extract oil flow rate EO_M signal to the power n using an exponential circuit 33 which includes a conventional type logarithmic amplifier 35, a multiplier 36, an operational amplifier 37, and a feedback element 38. Signal E_3 from flow transmitter 20A is applied to logarithmic amplifier 35 which in turn provides an output to a multiplier 36 whose output is multiplied with signal E_5 by multiplier 36. The product signal from multiplier 36 is applied to operational amplifier 37 having feedback element 38 connecting to its input and output. Feedback element 38 is in essence a function generator, which may be of the PC-12 type manufactured by Electronics Associates, that causes operational amplifier 37 to provide an output corresponding to $(EO_M)^n$. Signal E_2 from flow transmitter 20 is divided by the output from operation amplifier 37 by a divider 40 to provide signal E_6 .

A computer 34A operates in a similar manner as a_{LIM} characteristic computer to provide a signal E_7 corresponding to an a_{LIM} constant which is determined from the following empirically derived equation:

$$a_{LIM} = RO_{LIM} / (EO_{LIM})^n \quad (3)$$

Direct current voltages E_9 , E_{10} from source 26 correspond to the maximum possible flow rates RO_{LIM} and EO_{LIM} of the refined waxy oil and the extract oil within the physical constraints of the refining system. All direct current voltages from source 41 are with respect to a ground reference which is not shown. In the similar operation of computer 34A, as compared with computer 34, signal E_9 replaces signal E_2 , while signal E_{10} replaces signal E_3 . Computer 34A also received signal E_5 from converter 31.

Another characteristic constant b is determined in accordance with the following empirically derived equation:

$$b = \left\{ \frac{1}{1 + \left(\frac{RO_M}{EO_M} \right)} \right\} (S_{SEL}) (T_{SEL})^m \quad (4)$$

where S_{SEL} is a selected percent volume of solvent dosage, T_{SEL} is a selected refining temperature and m is a constant having a value in the range of 0.75 to 0.80, a preferred value being 0.775. It should be noted that although S_{SEL} and T_{SEL} are used, measured values of the charge oil flow rate and the refining temperature may be used in their place. A b constant computer 42 provides a signal E_{12} , corresponding to the constant b , in accordance with equation (4), signals E_2, E_3 flow from transmitter 20 and 20A, respectively, and direct current voltages $E_A, E_B, E_{16}, E_{17}, E_{25}$, and E_{26} from source 26. Direct current voltages $E_A, E_B, E_{16}, E_{17}, E_{25}$, and E_{26} correspond to flow rate CO_{SEL} , the refining temperature T_{SEL} , the term 1 in equation 4, the exponent m in equation 4, the maximum solvent flow rate SOL_{LIM} , and the term 100 in equation 1, respectively.

Referring to FIG. 3, computer 42 includes a divider 44 which divides signal E_2 with signal E_3 . Summing means 45 sums the resulting output from divider 44 with direct current voltage E_{16} and provides a corresponding sum signal to a divider 47. Divider 47 divides direct current voltage E_{16} by the sum signal from summing means 45 to provide an output. A divider 46 divides SOL_{LIM} signal E_{25} with CO_{SEL} voltage E_A to provide a signal to a multiplier 49 where it is multiplied with voltage E_{26} to provide a signal corresponding to S_{SEL} . The output from divider 47 is multiplied with the S_{SEL} signal by a multiplier 48 to provide a product signal to another multiplier 50. Direct current voltage E_B is raised to the power m by an exponential circuit 33A receiving voltage E_{17} . The output from exponential circuit 33A is applied to multiplier 50 where it is multiplied with the output from multiplier 48 to provide signal E_{12} .

The maximum refined oil and extract oil yields are constrained by the physical limitations of the refining unit. Thus the maximum refined oil yield occurs when the flow rate of the refined oil is at its physical limitation. The same is true for the extract oil. The determination of whether to operate the refining unit at the refined oil flow rate limitation RO_{LIM} or at the extract oil flow rate limitation EO_{LIM} is controlled by the constant a . When a is equal to or greater than a_{LIM} , the refinery unit is operated for the maximum possible refined oil flow rate RO_{LIM} . When a is less than a_{LIM} , the refinery unit is operated for the maximum possible extract oil flow rate EO_{LIM} .

Referring to FIG. 1, an electronic switch 54 is controlled by a comparator 57, comparing signals E_6 and E_7 , to pass signals E_{20}, E_{21} , from an EO_{LIM} computer 51, when signal E_6 from a constant computer 34 is equal to or greater than signal E_7 from a_{LIM} computer 34A and to block signals E_{20}, E_{21} from EO_{LIM} computer 51 when signal E_6 is less than signal E_7 . Similarly, comparator 57, through an inverter 58, controls an electronic switch 54A to block signals E_{22}, E_{23} from a RO_{LIM} computer 52 when signal E_6 is equal to or greater than signal E_7 and to pass signals E_{22}, E_{23} from RO_{LIM} computer 52 when signal E_6 is less than signal E_7 .

Signals E_{20} and E_{21} , corresponding to the charge oil flow rate CO_E and to the refining temperature T_E , respectively, are developed by EO_{LIM} computer 51 in accordance with the following equations:

$$RO_E = a (EO_{LIM})^n \quad (5)$$

$$CO_E = EO_{LIM} + RO_E \quad (6)$$

$$S_E = \left(\frac{SOL_{LIM}}{CO_E} \right) (100) \quad (7)$$

and

$$T_E = \left\{ \frac{b}{S_E} \left(1 + \frac{RO_E}{EO_{LIM}} \right) \right\}^{1/m} \quad (8)$$

where S_E is the solvent dosage in percent volume and SOL_{LIM} is the maximum possible flow rate of the solvent within the physical constraint of the refining unit. Source 26 provides direct current voltages E_{10}, E_{16}, E_{25} , and E_{26} and E_{27} to EO_{LIM} computer 51 which correspond to the following terms, respectively: EO_{LIM} , 1, SOL_{LIM} , 100 and $1/m$ in equations 5 through 8. Computer 51 also receives signals E_5, E_6 and E_{12} from digital-to-analog converter 31, a constant computer 34 and b constant computer 42, respectively. Referring now to FIG. 4, an exponential circuit 33B provides a signal corresponding to $(EO_{LIM})^n$ to a multiplier 60 in accordance with signals E_5, E_{10} . Multiplier 60 multiplies the signal corresponding to $(EO_{LIM})^n$ with a constant signal E_6 to provide a signal corresponding to the flow rate RO_E of the refined oil. Summing means 61 sums the EO_{LIM} signal E_{10} with the RO_E signal from multiplier 60 to provide signal E_{20} corresponding to the flow rate CO_E of the charge oil.

A temperature signal circuit 62 includes a divider 64 which divides the SOL_{LIM} voltage E_{25} with signal E_{20} and the resultant signal is applied to a multiplier 65. The signal from divider 64 is multiplied with voltage E_{26} so that multiplier 65 provides an output corresponding to the term S_E in equations 7, 8. A divider 66 divides the b constant signal E_{12} with the output from multiplier 65 to provide a signal to a multiplier 69.

The RO_E signal from multiplier 60 is divided by the EO_{LIM} signal E_{10} by a divider 70 in the temperature signal circuit 62 and the resulting output is summed with voltage E_{16} by summing means 71. Multiplier 69 multiplies the sum signal from summing means 71 with the signal from divider 66. An exponential circuit 33C provides T_E signal E_{21} in accordance with the product signal from multiplier 69 and voltage E_{27} .

Referring to FIG. 1, Signals E_{22}, E_{23} corresponding to the charge oil flow rate CO_R and to the refining temperature T_E , respectively, are developed by RO_{LIM} computer 52 in accordance with the following equations:

$$EO_R = \left(\frac{RO_{LIM}}{a} \right)^{1/n} \quad (9)$$

$$CO_R = EO_R + RO_{LIM} \quad (10)$$

$$S_R = \left(\frac{SOL_{LIM}}{CO_R} \right) (100) \quad (11)$$

and

$$T_R = \left\{ \frac{b}{S_R} \left(1 + \frac{RO_{LIM}}{EO_R} \right) \right\}^{1/m} \quad (12)$$

Computer 52 receives direct current voltages E_9 , E_{16} , E_{25} , E_{26} , and E_{27} , from source 26, corresponding to the RO_{LIM} , 1, SOL_{LIM} , 100 and $1/m$ terms in equations 9 through 12. The a , b , and n constant signals E_6 , E_{12} , and E_5 , respectively, are also applied to RO_{LIM} computer 52.

Referring to FIG. 5, a divider 75 in RO_{LIM} computer 52 divides signal E_{16} with signal E_6 and provides a resulting signal to an exponential circuit 33D. Another divider 76 divides the RO_{LIM} signal E_9 with the a constant signal E_6 to provide a signal to an exponential circuit 33D. Exponential circuit 33D provides a signal which corresponds to the extract oil flow rate EO_R to summing means 77 where it is summed with the RO_{LIM} signal E_9 to provide signal E_{22} corresponding to the charge oil flow rate CO_R .

The EO_R signal from exponential circuit 33D is applied to a temperature signal circuit 62A along with signals E_{12} , E_{16} , and E_{22} and with voltages E_9 , E_{25} , E_{26} , and E_{27} . Temperature signal circuit 62A provides T_R signal E_{23} in accordance with the applied signals and voltages and equation 12.

Referring again to FIG. 1, electronic switches 54B, 54C control the refining temperature and the charge oil flow rate to assure that refining temperature does not exceed a maximum temperature. The maximum temperature T_{MAX} is set at a temperature 10° to 20° F less than miscibility temperature T_{MISC} . When the value of the refining temperature, as determined by EO_{LIM} computer 51 or RO_{LIM} computer 52, exceeds T_{MAX} , T_{MAX} is used as the refining temperature and the charge oil flow rate is changed to provide the correct solvent dosage associated with the T_{MAX} temperature so that the desired quality of refined oil may be maintained. A charge oil flow rate CO_T signal E_{33} for the T_{MAX} condition is developed by a CO_T computer 90.

Source 26 provides a variable amplitude direct current voltage E_{35} corresponding to T_{MISC} and another direct current voltage E_{36} corresponding to a temperature greater than 10° but less than 20° F. The value of T_{MISC} may be determined experimentally from heating two volumes of N-methyl-2-pyrrolidone and one volume of charge oil until they become miscible. Subtracting means 91 subtracts voltage E_{36} from voltage E_{35} to provide a signal E_{38} , corresponding to T_{MAX} , to a comparator 57A, to CO_T computer 90 and to electronic switch 54C. Comparator 57A compares signal E_{38} with temperature signal E_{21} or E_{23} passed by switch 54 or 54A, respectively. Electronic switch 54B is controlled by comparator 57A, through an inverter 94, to pass the signals passed by electronic switch 54 or 54A when signal E_{38} is equal to or greater than signal E_{21} or E_{23} passed by switch 54 or 54A, respectively, and block the signals from switch 54 or 54A when signal E_{38} is less than signal E_{21} or E_{23} . Electronic switch 54C is controlled by comparator 57A to block signals E_{33} , E_{38} from CO_T computer 90 and subtracting means 91, respectively, when signal E_{28} is equal to or greater than signal E_{21} or E_{23} , and to pass signals E_{33} , E_{38} when signal E_{38} is less than signal E_{21} or E_{23} .

Computer 90 develops CO_T signal E_{33} in accordance with the following equations:

$$EO_T + 2a(EO_T)^n + o^2(EO_T)^{2n-1} = \frac{100(SOL_{LIM})(T_{MAX})}{b} \quad (13)$$

$$RO_T = a(EO_T)^n \quad (14)$$

$$CO_T = RO_T + EO_T \quad (15)$$

where EO_T , RO_T and CO_T are the flow rates for the extract oil, the refined oil and the charge oil when the refining temperature is T_{MAX} . The CO_T computer 90 receives direct current voltages E_{16} , E_{25} , E_{26} , E_{50} , and E_{51} from source 26, corresponding to the 1, SOL_{LIM} , 100, 2 and m terms, respectively, in equation 13. Source 26 provides another direct current voltage E_{52} to computer 90 which does not correspond to a term in the aforementioned equations. Computer 90 also receives the n constant signal E_5 , the a constant signal E_6 , the b constant signal E_{12} and the T_{MAX} signal E_{38} . Referring now to FIG. 6, voltage E_{52} is applied to a potentiometer 100 connected to ground having a movable wiper arm 101 which is positioned by a direct current motor 102. It should be noted that all direct current voltages from source 26 are with respect to a ground reference which is not shown. A voltage E_{60} present at wiper arm 101 corresponds to the extract oil flow rate EO_T for the T_{MAX} condition. Voltage E_{60} is raised to the n power by an exponential circuit 33E receiving the n constant signal E_5 . A multiplier 103 multiplies the output from exponential circuit 33E with the a constant signal E_6 to provide a signal E_{61} corresponding to the refined oil flow rate RO_T for the T_{MAX} condition. Signal E_{61} is multiplied with voltage E_{50} by a multiplier 108 to provide a product signal corresponding to the term $2a(EO_T)^n$ in equation 13.

The a constant signal E_6 is effectively squared by a multiplier 109 and the resulting signal is applied to another multiplier 110. The n constant signal E_5 is multiplied with voltage E_{50} by a multiplier 111 and a resulting signal has voltage E_{16} subtracted from it by subtracting means 114. An exponential circuit 33F raises signal E_{60} to a power determined by the output from subtracting means 114 and the resulting signal is multiplied with the signal from multiplier 109 by multiplier 110. Multiplier 110 provides a signal corresponding to the term $a^2(EO_T)^{2n-1}$ in equation 13. Summing means 115 sums signal E_{60} and the signals from multipliers 108, 110 to provide a signal, corresponding to the left side of equation 13, to subtracting means 116.

Signal E_{38} is raised to the power 0.775 by an exponential circuit 33G, receiving signal E_{38} and voltage E_{51} . The SOL_{LIM} voltage E_{25} is multiplied with voltage E_{26} by a multiplier 120 and the product signal is multiplied with the signal from exponential circuit 33G by another multiplier 121. The product signal from multiplier 121 is divided with the b constant signal E_{12} by a divider 122 to provide a signal to subtracting means 116 corresponding to the right side of equation 13. Subtracting means 116 subtracts the signal from divider 122 from the signal from summing means 115 to provide an output. When the output from subtracting means 116 is zero, signal E_{60} corresponds to the correct value of EO_T . The output from subtracting means 116 is amplified by an amplifier 125 to energize motor 102, when the output from subtracting means 116 is positive. Motor 102 moves wiper arm 101 of potentiometer 100 in a direction to reduce signal E_{60} until the output from subtracting means 116 is zero. Similarly, when the output from subtracting means 116 is negative, motor

102 moves wiper arm 101 in a direction to increase signal E_{60} until the output from subtracting means 116 is zero.

Summing means 118 sum EO_T signal E_{60} with the RO_T signal from multiplier 103 to provide the CO_T signal E_{33} .

Referring back to FIG. 1, the signals passed by electronic switch 54B or 54C are applied to a double pole, single throw switch 130 which may be of the 'momentary on' type. An operator closes switch 130 to provide the signals from electronic switch 54B or 54C as signals E_1 , E_{19} to flow recorder controller 6 and to temperature recorder controller 14, respectively, to adjust their set points accordingly.

As conditions change, the operator may change the amplitudes of the voltage from source 26 or the computed constant signals may change accordingly. The operator can then control the charge oil flow rate and the refining temperature by closing switch 130 to affect the refining of the charge oil in accordance with the new condition or conditions.

The device of the present invention, as heretofore described, controls a solvent refining unit so that refining unit operates at a maximum capability. The solvent refining unit is operated at a temperature substantially less than the temperature at which the charge oil and the solvent become miscible. The solvent refining unit has been controlled to operate at the maximum refined oil flow rate possible when the refined oil flow rate is limiting and the computed refining temperature is substantially less than the miscibility temperature. The solvent refining unit has also been controlled to operate at the maximum extract oil flow rate possible when the extract oil flow rate is limiting and the computed refining temperature is substantially less than the miscibility temperature.

I claim:

1. A control system for a solvent refining unit which treats charge oil with a solvent in a refining tower to yield raffinate and extract-mix, strippers separate the solvent from the raffinate and from the extract-mix to provide refined waxy oil and extract oil, respectively, the solvent is returned to the tower and the refined waxy oil is subsequently dewaxed to provide refined oil, comprising means for controlling the operation of the refining unit, first means connected to the control means for providing control signals to the control means to operate the refining unit for a predetermined time period at a predetermined solvent dosage-temperature combination so as to provide refined oil of a desired quality, means for measuring at least one condition of the extract oil and one condition of the refined waxy oil and providing signals corresponding thereto, means for measuring at least one property of the charge oil and providing a corresponding signal, signal means for providing signals corresponding to limitations of operating parameters of the refining unit and the refining operation, means connected to the condition measuring means, to the property measuring means and to the limitation signal means for determining which operating parameter is limiting and providing signals corresponding thereto, and second means connected to the determining means and to the control means for providing control signals to the control means after the predetermined time period in accordance with the

signals from the determination means to control the operation of the refining unit so that the refining unit operates at a maximum capability while maintaining the quality of the refined oil.

- 5 2. A system of the kind described in claim 1 in which
 the solvent is N-methyl-2-pyrrolidone and the solvent
 flows at a maximum possible rate SOL_{LIM} .

10 3. A system as described in claim 2 in which the first
 control signal means includes means for providing
 direct current control signals corresponding to a
 selected charge oil flow rate CO_{SEL} and to a selected
 refining temperature T_{SEL} , and switching means con-
 necting the CO_{SEL} , T_{SEL} signal means to the control
 15 devices for momentarily applying the CO_{SEL} and the
 T_{SEL} signals to the control devices to control the refin-
 ing unit so that the refining unit operates with the
 selected charge oil flow rate and refining temperature
 20 until other control signals are applied to the control
 devices.

25 4. A system as described in claim 3 in which the
 signal means provides signals corresponding to the
 maximum possible flow rates EO_{LIM} and RO_{LIM} of the
 extract oil and the refined waxy oil, respectively.

30 5. A system as described in claim 4 in which the mea-
 sured property of the charge oil is the viscosity, and the
 measured conditions of the extract oil and the refined
 waxy oil are the extract oil flow rate EO_M and the
 35 refined waxy oil flow rate RO_M ; and the determining
 means includes means connected to the property mea-
 suring means for providing a signal corresponding to a
 correlation constant n in accordance with the viscosity
 40 signal from the property measuring means, means con-
 nected to the condition measuring means and to the n
 constant signal means for providing a signal cor-
 responding to an a constant in accordance with the
 45 EO_M and RO_M signals from the condition signal means
 and the n constant signal from the n factor signal
 means, means connected to the limitation signal means
 for providing a signal corresponding to an a_{LIM} constant
 50 in accordance with the EO_{LIM} and RO_{LIM} signals from
 the limitation signals means, and a comparator con-
 nected to the a constant signal means and to the a_{LIM}
 constant signal means for comparing the a constant
 signal to the a_{LIM} constant signal to determine whether
 the refined waxy oil flow rate is the limiting operating
 parameter, the extract oil flow rate is the limiting
 operating parameter, or the refining unit is balanced.

55 6. A system as described in claim 5 in which the n
 constant signal means includes memory means in vari-
 ous values of n have been stored, and selection means
 connected to the memory means and to the viscosity
 measuring means for selecting the proper n value from
 the memory means in accordance with the viscosity
 signal from viscosity measuring means; the a constant
 60 signal means is an a constant analog computer provid-
 ing the a constant signal in accordance with the follow-
 ing first equation:

$$a = RO_M / (EO_M)^n;$$

- 65 and the a_{LIM} constant signal means is an a_{LIM} constant analog computer providing the a_{LIM} constant signal in accordance with the following second equation:

$$a_{LIM} = RO_{LIM}/(EO_{LIM})^n$$

7. A system as described in claim 6 in which the comparator provides a signal having one amplitude when the a constant signal is equal to or greater than the a_{LIM} constant signal and another amplitude when the a constant signal is less than the a_{LIM} constant signal; and the determining means includes a b constant analog computer receiving direct current voltages and being connected to the condition measuring means and to the first control means for providing a signal corresponding to the b constant in accordance with the EO_M and RO_M signals from the condition measuring means, the S_{SEL} and T_{SEL} signals from the CO_{SEL} , T_{SEL} signal means, the direct current voltages and the following third equation:

$$b = \left\{ \frac{1}{1 + \left(\frac{RO_M}{EO_M} \right)} \right\} (S_{SEL}) (T_{SEL})^m$$

where m is a constant having a value within the range of 0.75 to 0.80; and the second control signal means includes means connected to the a constant computer, to the b constant computer and to the n constant signal means and receiving direct current voltages for providing signals corresponding to the charge oil flow rate CO_E and to the refining temperature T_E for the condition where the extract oil flow rate is at its maximum possible rate EO_{LIM} ; means connected to the a and b constant computers and to the n constant signal means for providing signals corresponding to the charge oil flow rate CO_R and to the refining temperature T_R for the condition where the refined waxy oil flow rate is at its maximum possible rate RO_{LIM} ; switching means connected to the CO_E , T_E signal means, to the CO_R , T_R signal means and to the comparator and controlled by the signal from the comparator to pass the CO_R and T_R signals from the CO_R , T_R signal means when the signal from the comparator is of the one amplitude and to pass the CO_E and the T_E signals from the CO_E , T_E signal means when the signal from the comparator is of the other amplitude; subtracting means receiving direct current voltages, corresponding to the miscible temperature T_{MISC} of the charge oil and the N-methyl-2-pyrrolidone and to a temperature T_1 occurring within the range of 10° to 20° F. for subtracting the T_1 voltage from the T_{MISC} voltage to provide a signal corresponding to the maximum permissible refining temperature T_{MAX} ; means connected to the a and b constant computers, to the n constant signal means and to the subtracting means and receiving direct current voltages for providing a signal corresponding to the charge oil flow rate CO_T for the condition where the refining temperature is at its maximum permissible level T_{MAX} ; a second comparator connected to the first switching means and to the subtracting means for comparing the T_{MAX} signal with the T_E or T_R signal passed by the first switching means and providing a signal of one amplitude when the T_R or T_E signal is less than the T_{MAX} signal and of another amplitude when the T_R or T_E signal is equal to or greater than the T_{MAX} signal, and second switching means connected to the subtracting means, to the first switching means, to the CO_T signal means, to the control devices and to the second comparator for blocking the signals from the first switching means, from the subtracting means and from the CO_T signal means during the predetermined time period and for passing the CO_E ,

T_E or the CO_R , T_R signals from the first switching to the control devices as the control signals after the predetermined time period in response to the signal from the second comparator being of the one amplitude and for passing the CO_T signal from the CO_T signal means and the T_{MAX} signal from the subtracting means to the control devices as the control signals after the predetermined time period in response to the signal from the second comparator being of the other amplitude.

8. A system as described in claim 7 in which the CO_E , T_E signal means is an analog computer providing the CO_E and the T_E signals in accordance with the following fourth through seventh equations:

$$RO_E = a (EO_{LIM})^n$$

$$CO_E = RO_E + EO_{LIM}$$

$$S_E = \left(\frac{SOL_{LIM}}{CO_E} \right) (100)$$

and

$$T_E = \left\{ \frac{b}{S_E} \left(1 + \frac{RO_E}{EO_{LIM}} \right) \right\}^{1/m}$$

where RO_E and S_E are the refined waxy oil flow rate and the solvent dosage for the condition where the extract oil is flowing at its maximum possible flow rate EO_{LIM} and the received direct current voltages correspond to the term 100 in the sixth equation and the term 1 and the exponent m in the seventh equation, where m has a value within the range of 0.75 to 0.80; the CO_R , T_R signal means is an analog computer providing the CO_R , and the T_R signals in accordance with the following eighth through 11th equations:

$$EO_R = \left(\frac{RO_{LIM}}{a} \right)^{1/n}$$

$$CO_R = RO_{LIM} + EO_R$$

$$S_R = \left(\frac{SOL_{LIM}}{CO_R} \right) (100)$$

and

$$T_R = \left\{ \frac{b}{S_R} \left(1 + \frac{RO_{LIM}}{EO_R} \right) \right\}^{1/m}$$

where EO_R and S_R are the extract oil flow rate and the solvent dosage, respectively, for the condition where the refined waxy oil is flowing at its maximum possible flow rate RO_{LIM} and the received direct current voltages correspond to the term 100 in the 10th equation and the term 1 and the exponent m in the 11th equation; and the CO_T signal means is an analog computer providing the CO_T signal in accordance with the following 12th through 14th equations:

$$EO_T + 2a(EO_T)^n + a^2(EO_T)^{2n-1} = \frac{100(SOL_{LIM})(T_{MAX})^m}{b}$$

$$RO_T = a(EO_T)^n$$

and

$$CO_T = RO_T + EO_T$$

where EO_T and RO_T are the extract oil and refined waxy oil flow rates, respectively, for the condition where the refining temperature is at the maximum permissible level T_{MAX} and where the received direct current voltages correspond to the exponent m and the term 2 in the 12th equation.

9. A method for controlling a solvent refining unit in which charge oil is treated with solvent in a refining tower to yield raffinate and extract-mix, strippers

separate the solvent from the raffinate and extract-mix to provide refined waxy oil and extract oil, respectively, the solvent is returned to the tower and the refined waxy oil is subsequently dewaxed to provide refined oil, which comprises refining the charge oil for a predetermined time period at a predetermined solvent dosage and a predetermined temperature to achieve a desired quality of refined oil, measuring at least one property of the charge oil, measuring at least one condition of the refined waxy oil and one condition of the extract oil, providing signals corresponding to the measurements, providing signals corresponding to limitations of the refining unit and the refining operation, utilizing the signals to determine which operating parameter is limiting, and controlling the operation of the refining unit after the predetermined time period in accordance with the determination.

10. A method as described in claim 9 in which the solvent is N-methyl-2-pyrrolidone.

11. A method as described in claim 10 in which the measured property of the charge oil is the viscosity, the limitation signals correspond to the maximum possible flow rates EO_{LIM} and RO_{LIM} of the extract oil and the refined waxy oil, respectively, and to the maximum permissible refining temperature T_{MAX} , the measured conditions of the extract oil and the refined waxy oil are their flow rates EO_M and RO_M , respectively, and the charge oil flow rate and the refining temperature are controlled in accordance with the determination.

12. A method as described in claim 11 in which the determining step includes providing an n constant signal in accordance with the measured viscosity signal, providing an a constant signal in accordance with the measured extract oil flow rate EO_M signal, the measured refined waxy oil flow rate RO_M signal, the n constant signal and the following equation:

$$a = RO_m / (EO_M)^n,$$

providing an a_{LIM} constant signal in accordance with the maximum possible extract oil and refined waxy oil flow rates EO_{LIM} and RO_{LIM} signals, respectively, the n factor signal and the following equation:

$$a_{LIM} = RO_{LIM} / (EO_{LIM})^n,$$

providing an m constant signal, having a value within the range of 0.75 to 0.80, and providing a b constant signal in accordance with the selected dosage S_{SEL} signal, the selected refining temperature T_{SEL} signal, the measured extract oil and refined waxy oil flow rates EO_M and RO_M signals, direct current voltages corresponding to a value of 1 and to an exponent m , respectively, and the following equation:

$$b = \left\{ \frac{1}{1 + \frac{RO_M}{EO_M}} \right\} (S)(T)^m.$$

13. A method as described in claim 12 in which the determining step includes comparing the a constant signal and the a_{LIM} constant signals, providing a comparison signal having one amplitude when the a constant signal

is less than the a_{LIM} constant signal and another amplitude when the a constant signal is equal to or greater than the a_{LIM} constant signal, providing control signals CO_E and T_E corresponding to a flow rate for the charge oil and a refining temperature, respectively, when the comparison signal is of the one amplitude, providing control signals CO_R and T_R when the comparison signal is of the other amplitude, determining the miscible temperature of the charge oil and the solvent, providing a signal corresponding to a maximum refining temperature T_{MAX} which is substantially less than the miscible temperature, comparing the T_R or T_E signal, whichever is provided, with the T_{MAX} signal, providing a second comparison signal having one amplitude when the T_R or T_E signal is less than the T_{MAX} signal and another amplitude when the T_R or T_E signal is equal or greater than the T_{MAX} signal, providing a CO_T signal, corresponding to a flow rate for the charge oil, and the T_{MAX} signal as control signals after the predetermined time period

20 when the second comparison signal is of the other amplitude, and providing the CO_R , T_R signals or the CO_E , T_E signals as control signals after the predetermined time period when the second comparison signal is of the one amplitude.

14. A method as described in claim 13 in which the CO_R and T_R signals are provided in accordance with the n constant signal, the RO_{LIM} signal, the SOL_{LIM} signal, the a constant signal, direct current voltages corresponding to values of 1, 100, and m and the following equations:

$$EO_R = \left(\frac{RO_{LIM}}{a} \right)^{1/n}$$

$$CO_R = EO_R + RO_{LIM}$$

$$S_R = \left(\frac{SOL_{LIM}}{CO_R} \right) (100)$$

and

$$T_R = \left\{ \frac{b}{S_R} \left(1 + \frac{RO_{LIM}}{EO_R} \right) \right\}^{1/m}$$

The CO_E and T_E signals are provided in accordance with the n factor signal, the EO_{LIM} signal, the SOL_{LIM} signal, the a constant signal, the direct current voltages corresponding to the values of 1, 100 and m and the following equations:

$$RO_E = a (EO_{LIM})^n$$

$$CO_E = RO_E + EO_{LIM}$$

$$S_E = \left(\frac{SOL_{LIM}}{CO_E} \right) (100)$$

and

$$T_E = \left\{ \frac{b}{S_E} \left(1 + \frac{RO_E}{EO_{LIM}} \right) \right\}^{1/m}$$

and

the CO_T signal is provided in accordance with the T_{MAX} signal, and m and n factor signals, the a and b constants signals, the SO_{LIM} signal, direct current voltages corresponding to the values of 1, 2, and 100, and the following equations:

$$EO_T + 2a(EO_T)^n + a^2 EO_T^{2n-1} = \frac{100(SO_{LIM}(T_{MAX})^m)}{b}$$

$$RO_T = EO_T)^n$$

$$5 \quad CO_T = RO_T + EO_T$$
